JAR WRENCH

Philip F. Marsella and Ferdinando Marsella,
Seneca Falls, N. Y.

Application June 23, 1936, Serial No. 86,854

3 Claims. (Cl. 81—3.1)

This invention relates to wrenches primarily designed for the removal of jar caps, and the general object of the invention is to provide the handle of the wrench with a plurality of jar cap engaging members of different sizes or diameters, the handle of the wrench being so connected to these jar engaging members that as the handle is closed, the particular jar engaging member in use may be contracted around the jar cap to either put the cap in position or remove it from a jar.

Another object of the invention is to provide a construction of this character in which the outermost jar engaging member is formed integral with the handle members and in which a plurality of successively smaller jar engaging members are pivoted within the loop of the first named engaging member so that they may be turned down out of position when not wanted, to permit the engaging member which fits the jar being opened or closed, to be used.

A further object is to so form the ends of the handle members that the handle members may be used for removing the rubber gaskets or washers which are commonly used on jars such as Mason jars, between the jar and the cap.

Other objects will appear in the course of the following description.

Our invention is illustrated in the accompanying drawing wherein:

Figure 1 is an edge face view of the wrench;
Figure 2 is a longitudinal section of the wrench with two of the cap gripping portions raised out of operative position;

Figure 3 is a fragmentary inside face view of the extremity of one of the handle members.

Referring to the drawing, 10 designates an open ring-shaped member which describes a segment of a circle and terminates in two outwardly extending handle members 11 and 11^a, these handle members being shown as being formed integral with the cap clamping element 10. One of the handle members, as 11, adjacent its extremity is bent inward at 12 and then extends outward to form a beveled edge 13 for a purpose to be later stated, the inner face of this portion 13 being knurled or toothed slightly, as at 14. Extending through the handle members 11 and 11^a adjacent the clamping member 10 is a pin 15, which pin is headed at its ends, as at 16, and passes loosely through openings in the handle members 11 and 11^a.

Disposed within and approximately concentric to the clamping member 10 is a smaller clamping member 17, which is arcuate in form and has

its ends extending toward the extremities of the handle members 11 and 11^a, as at 18. Similar clamping rings 19 and 20 are disposed within the clamping ring 17 and approximately concentric to each other, these clamping rings having the portions 18 which extend toward the extremities of the handle members 11 and 11^a and through which the pin 15 passes. The clamping members 10, 17, 19 and 20 are resilient and these members are urged to an expanded condition by reason of their resilience, the expansion of the members being limited by the heads 16 of the pin 15. It will be obvious now that if the handle members 11 and 11^a be grasped by the hand and forced together, that one or all of the clamping rings 10, 17, 19 and 20 will be contracted and that when pressure on the handle members is released, the clamping rings will expand to the extent permitted by the pin 15.

If it be desired to use the outermost clamping ring 10, all the other rings may be turned out of the way and the clamping ring 10 be used for screw or other caps having a relatively large diameter, and that if it be desired to use the next smaller diameter as, for instance, the ring 17, this ring is turned into the plane of the ring 10 while the inner rings 19 and 20 are turned out of the way, and this ring 19 clamped upon the object. The same operation is used where rings 19 or 20 are desired. By having these rings of different diameters, it is obvious that the wrench may be used on jars, bottles or other containers for the removal or placement of caps or closures thereon without regard to the differing diameters of the stoppers, caps or closures, and that thus this device is adapted for use with containers, the caps of which have various diameters, it being understood, however, that the cap 10 is intended for the caps of standard containers having a standard diameter.

Certain containers have a cap which is screwed down or forced down upon a rubber gasket. These caps or closures are often times difficult to remove because of the suction with which the caps are held down upon this gasket, and a knife or like implement must be inserted between the rubber gasket and the cap or closure in order to remove it. In our construction, the wedge-shaped extremity 14 of the handle member 11 is adapted for this very purpose, to be inserted between the gasket and the cap and to pry upward on the cap or on the gasket itself.

We have illustrated the handle member 11^a as terminating short of the handle member 11 and as having riveted thereto a strip of metal design-

nated 21 which extends from the handle member 11^a to a point opposite the extremity of the handle member 11, and is then extended toward the clamping end of the handle member 11^a.
5 This strip of metal 21 is bent laterally, then outward, then at right angles to the length of the handle member 11^a, then inward and laterally, and rivet 22 extends through the two thicknesses of this strip. A second strip 23 is also riveted
10 to the outer face of the handle member 11^a and extends into approximate contact with the re-folded end of the strip 21. The inner face of the loop 24 thus formed is knurled, this knurled face confronting the knurled inner face of the portion
15 13 or handle member 11. By inserting the chisel-pointed or wedge-shaped end 14 into the space between the rubber gasket and the jar cap and then clamping the jar cap between the knurled surface on the loop 24 and the knurled surface
20 on the inner face of the portion 13, the jar cap can be grasped and removed without touching it with the fingers. Disposed between the returned end portion of the strip 21 and held in place by the rivets 22 and 25 is a member 26 which at one
25 end extends below the loop 24 and is then extended parallel thereto, the edge of this member being sharpened and the member being pointed at its extremity so that it constitutes a can opening tool, the point of the blade 27 being inserted
30 through the can while the loop 24 constitutes a head adapted to rest upon the top of the can while the whole device is oscillated so as to cause the blade to cut the can in the manner of an ordinary can opening blade. The member 26
35 also extends above the loop 24 and rearward thereof, and is curved to form a hook 28 which constitutes a bottle cap remover, the loop 24 constituting a head to rest upon the top of the bottle cap and fulcrum against it while the hook
40 pulls the bottle cap off.

It will be obvious that this device provides in one structure, means for opening a large number of closures of different character, and that it may be used for placing jar caps on jars, as well as removing the caps therefrom.

45 While we have illustrated certain details of construction and arrangement of parts which we believe to be particularly effective, we do not wish to be limited to these details except as defined in the accompanying claims. Thus it is within the purview of our invention to provide more clamping members than the four which are shown, and to provide a nest of smaller clamping members to open and close small containers. The members 10, 11, 19 and 20 are for the purpose of opening and closing containers such as Mason fruit jars and other similar jars having caps which screw down or which will unscrew. The terminal portion 14 of handle member 11 and the

knurled portion 24 are for the purpose of pulling out rubber gaskets on jars which have unscrewable caps or covers as, for instance, the "Ideal" or "Atlas" jars. In many cases where a person tries to open jars of this type, the suction will hold the cap very tenaciously to the jar. The parts 14 and 24 will be used to loosen the gasket or washer, break the compression and remove the cover.

5 What is claimed is:—

10 1. A cap wrench, including an outer substantially arcuate clamping member having opposed handle members extending from its ends and a plurality of approximately arcuate clamping members, successively decreasing in diameter, 15 disposed within the outer clamping member and each having shank portions at its ends disposed approximately parallel to the handle portions of the outer member, all of said members being resilient, the resilience of said members urging 20 their ends outward, a pin extending loosely through the handle members and through the shank portions of the inner clamping members and pivoting the shank portions of all the inner clamping members to the handle members for 25 movement into or out of the plane of the outer clamping member, said pin permitting the compression of the handle members towards each 30 other and the corresponding contraction of the clamping members.

2. A cap wrench, including an outer substantially arcuate clamping member of resilient material having opposed handles extending from its ends and an inner arcuate clamping member smaller in diameter than the first named clamping member and normally disposed within said member and in the same plane thereas, the inner member having shank portions at its ends extending into the space between the inner ends of the handles, the resilience of the clamping members urging their ends outward, and means pivotally engaging the handle members with said shanks but permitting the handle members to be forced towards each other to thereby contract the clamping members.

45 3. A cap wrench, including an outer substantially arcuate member having handles extending from its ends and a plurality of inner arcuate clamping members each having its ends operatively pivoted to the handles for independent 50 movement into or out of the plane of the first named clamping member, all of the clamping members being of resilient material, the resilience of the material urging the ends of all of said clamping members outward and urging the 55 handles away from each other.
